UNITED STATES PATENT OFFICE.

CHARLES H. PERKETT, OF WILLSBORO, NEW YORK.

COW-TAIL HOLDER.

972,021.

Specification of Letters Patent.

Patented Oct. 4, 1910.

Application filed August 31, 1909. Serial No. 515,544.

To all whom it may concern:

Be it known that I, CHARLES H. PERKETT, a citizen of the United States, residing at Willsboro, in the county of Essex and State 5 of New York, have invented new and useful Improvements in Cow-Tail Holders, of which the following is a specification.

This invention relates to a device for application to cows for the purpose of holding 10 the cow's tail and preventing her from kicking or switching the tail.

The primary object of the invention is to provide a simple and inexpensive construction of device which will effectually serve 15 this dual purpose.

A further object of the invention is to provide a combined anti-kicking and tail holding attachment which will accommodate itself to cows of different sizes.

20 With these and other objects in view, the invention consists of the features of construction, combination and arrangement of parts hereinafter fully described and claimed, reference being had to the accompanying drawing, in which:—

Figure 1 is a perspective view showing the application of the invention as in use. Fig. 2 is a top plan view of the device on an enlarged scale. Fig. 3 is a detail section 30 through the free ends of the jaws of one of the shackles, showing the locking connection.

The device comprises a pair of shackles 1 and 2 which are adapted for application to the hind legs of the animal, as shown in Fig. 35 1. These shackles are duplicates in construction, each being of elliptical form and comprising outer and inner longitudinally bowed jaws or members 3 and 4 pivotally connected at their rear ends, as indicated at 40 5. The opposite or forward ends of the jaws are respectively provided with short and long parallel arms 6 and 7, the arm 6 of the jaw 3 being longitudinally slotted or bifurcated to form a keeper, while the longer arm 45 7 of the jaw 4 is provided with a slot 8 for the reception of a latch 9 which is pivotally mounted therein and provided with a beveled and hooked locking end 10 to engage said keeper. The inner end of the latch 9 is connected by a spring 11 with the extremity of the arm 7, which spring serves to normally maintain the latch in locking position.

The jaws 3 and 4 are sufficiently bowed to 50 form a shackle having a receiving opening large enough for the application of the shackles to the legs of different sized cows.

In order to clamp the shackles in position, each shackle is provided with a longitudinally extending bowed clamping spring 12 bent at its rear end to provide a U-shaped 60 portion 13 which is riveted or otherwise fixed, as indicated at 14, to the rear ends of the jaw to yieldingly connect the same and to normally hold said jaws closed. The opposite or free end 15 of the spring slidably 65 engages a guide loop 16 carried by the inner jaw 4, by which such end of the spring is retained in position and the body of the spring permitted to expand and retract to accommodate itself to variations in the sizes 70 of the legs of cows to which the shackle is applied. It will be understood that in applying each shackle, the latch is retracted, the shackle opened and applied, and then allowed to close by the action of the spring 12, 75 whereupon the latch will automatically engage the keeper 6 to hold the shackle closed about the leg.

The two shackles are connected by a cross bar 17 extending between the central portions of their inner jaws 4, by which they are coupled and held in determined relation. A spring clip 18 is preferably secured to this cross bar and has its free end bearing on the inner arm of one of the fastening devices, to 80 serve as a support by which the device may be suspended when not in use. A tail holder 19, in the form of a loop or eye, is arranged between the rear ends of the shackles 1 and 2 and is provided with parallel arms 20 which 85 are fitted to slide in openings 23 in the bar 17 and project forwardly therefrom. An eye bolt or pin 21 connects the forward ends of these arms and serves as an attachment for the rear ends of link rods or other flexible connections 22 which extend therefrom to the inner ends of the latches 9, and thus connect said holder with the latches, so that by a rearward sliding motion of the holder the latches may be simultaneously swung on their pivots 100 against the resistance of the springs 11 to open the shackles and permit of their ready removal from the animal. In the use of the device, after the shackles have been fitted upon the legs of the animal, the tail is inserted down through the holder 19, whereby it will be held so that it cannot be switched by the cow. At the same time the shackles engaging the legs will prevent the cow from kicking.

From the foregoing description, the construction and mode of use of my improved

tail holder and anti-kicking device will be readily understood, and it will be seen that a device of this character is provided which is effective in use and will prove of great convenience to farmers and others in enabling them to prevent a cow from kicking or switching her tail while she is being milked.

I claim:—

- 10 1. A device of the character described comprising a pair of shackles, latches for holding the shackles closed, and a cow tail holder carried by the shackles and connected with the latches, whereby upon a rearward movement of said holder the latches may be retracted.
- 15 2. A device of the character described comprising shackles, each embodying a pair of pivoted jaws, leg clamping springs carried by the shackles, latches for holding the jaws thereof closed, a tail holder carried by the shackles, and means operable thereby for retracting said latches.
- 20 3. A device of the character described comprising a pair of shackles, each embodying a pair of pivotally connected jaws, a clamping spring associated with each of said shackles to engage the leg of the animal and hold the shackles thereon, and a tail holder carried by said shackles.
- 25 4. A device of the character described comprising leg engaging shackles, each em-

bodying pivoted jaws, latches for holding the jaws closed, a tail holder carried by and movably mounted on the shackles, and a connection between said holder and the latches whereby the latter may be simultaneously retracted.

35

5. A device of the character described comprising a pair of shackles, each embodying a pair of pivoted jaws, spring actuated latches for locking the jaws of the shackles in closed position, a tail holder slidably mounted upon the shackles, and connections between said tail holder and the latches, whereby the latter may be simultaneously retracted.

40

6. A device of the character described comprising a pair of connected shackles, each embodying a pair of jaws, leg clamping springs yieldingly connecting the jaws of the respective shackles, latches for locking the jaws of the shackles in closed position, springs for normally holding said latches in locking position, a tail holder slidably mounted on the shackles, and connections between said holder and the latches whereby the latter may be simultaneously retracted.

45

In testimony whereof I affix my signature in presence of two witnesses.

CHARLES H. PERKETT.
